(57) **CLAIM**

The ornamental design for an accumulator unit, as shown and described.

DESCRIPTION

FIG. 1 is a right side view of an accumulator unit in accordance with the invention;

FIG. 2 is a front view thereof;

FIG. 3 is a top view thereof;

FIG. 4 is a rear view thereof;

FIG. 5 is a left side view thereof;

FIG. 6 is a bottom view thereof; and,

FIG. 7 is a perspective view thereof.

The broken lines shown in the drawings represent unclaimed subject matter and form no part of the claimed design.
